UNITED STATES PATENT OFFICE.

ALFRED E. DUBAY, OF BROOKLYN, NEW YORK, ASSIGNOR TO DOMESTIC MILLS PAPER COMPANY, OF NEW YORK, N. Y., A CORPORATION OF NEW YORK.

WRAPPER FOR AUTOMOBILE-TIRES, &c.

1,255,086.

Specification of Letters Patent. Patented Jan. 29, 1918.

Application filed December 10, 1915. Serial No. 66,070.

To all whom it may concern:

Be it known that I, ALFRED E. DUBAY, of Brooklyn, in the county of Kings, and in the State of New York, have invented a certain new and useful Improvement in Wrappers for Automobile-Tires, &c., and do hereby declare that the following is a full, clear, and exact description thereof.

The object of my invention has been to provide a wrapper for automobile tires and other similar shaped objects, which shall have, among others, the advantages of being simple and cheap; of being capable of application to an annular form like an automobile shoe, as well as to a cylindrical form, and of being so constructed that it will not separate and expose parts of the shoe or tire or other object being wrapped, between its convolutions; and to such ends my invention consists in the wrapper for automobile tires, etc., hereinafter specified.

In the accompanying drawings,

Figure 1 is a side elevation of an automobile shoe partly wrapped with my wrapper;

Fig. 2 is a sectional view of a portion of Fig. 1 in the central plane of the tire;

Fig. 3 is a plan view, and Fig. 4 a cross-sectional view of one form of wrapper embodying my invention;

Figs. 5 and 6 are, respectively, a plan view and a cross-section of another form of wrapper embodying my invention.

While I have illustrated my invention by the embodiments thereof which are the best known to me, such embodiments are to be regarded as typical only, and my invention is not to be confined thereto.

Referring first to the form of my invention shown in Figs. 1 and 2: My invention consists of a strip of paper or similar non-self-sustaining material 1, having shoulders 2 formed at or near its edges. The shoulders are preferably on opposite sides of the strip for a reason which will later appear. In the form of my invention shown in Figs. 1 and 2, the shoulders are formed by bending the edges of the strip over upon the body thereof, and in that particular form now being considered, the edges of the strip 1 are bent along lines 3 to form a double edge, which is then bent over along lines 4, so that a shoulder or bead of double thickness of paper is formed along each edge of the strip. When the strip is wrapped spirally around the tire, the strips, as shown in

Fig. 2, are overlapped, the dispositions of the shoulders on opposite sides of the strip effecting a continuous shoulder on the forward edge of the strip as it is wound about the tire, thus interlocking the shoulders upon adjacent edges of the neighboring turns of the strip. This interlocking of the shoulders prevents the neighboring turns of the strip separating from each other and exposing the shoe therebetween. The strip is applied to the shoe under sufficient tension so that the shoulders are prevented from disengaging.

It is obvious that the shoulders on opposite sides of a wrapping strip can be formed in many different ways. They can be formed by simply folding over the edge once instead of twice, or, as shown in Figs. 5 and 6, the edges of the strip may be folded over once, a thread or twine 5, being placed in the fold and the fold, if desired, being pasted down.

I claim:

1. A temporary wrapper consisting of a strip of non-self-sustaining material having a shoulder formed along each edge, the shoulders being upon opposite faces of the strip, said shoulders having inner sides adapted to overlap and abut one another when the strip is wrapped about the body to be covered.

2. A temporary wrapper consisting of a strip of paper or similar material having a shoulder formed along each edge, the shoulders being upon opposite faces of the strip, said shoulders having inner sides adapted to overlap and abut one another when the strip is wrapped about the body to be covered.

3. A wrapper comprising a strip of non-self-sustaining material having shoulders formed on its opposite edges, each shoulder being formed by bending over the material of the strip a plurality of times, the shoulders being formed on opposite faces of the strip.

4. A wrapper comprising a strip of paper or similar material having shoulders formed on its opposite edges, each shoulder being formed by bending over the material of the strip a plurality of times, the shoulders being formed on opposite faces of the strip.

5. A temporary wrapper formed of a strip of paper, having protuberances upon each edge, said protuberances being upon

2
opposite faces of the strip; said strip being flat between the protuberances, said protuberances having inner sides adapted to overlap and abut one another when the strip is wrapped about the body to be covered.

6. In combination, a body to be covered and a temporary covering therefor comprising a strip of non-self-sustaining material wound in overlapping turns thereabout, the 10 overlapping edges of said turns being provided with abutting protuberances.

7. In combination, a body to be covered and a temporary covering therefor comprising a strip of non-self-sustaining material wound in overlapping turns thereabout, 15 protuberances being provided on opposite sides of said strip, the protuberances of each turn overlapping and abutting the similar edges of the adjacent turns.

In testimony that I claim the foregoing 20 I have hereunto set my hand.

ALFRED E. DUBEY.
